UNITED STATES PATENT OFFICE.

CHARLES F. SCHNEBELIN, OF PEORIA, ILLINOIS, ASSIGNOR TO STUBER & KUCK, OF PEORIA, ILLINOIS, A FIRM.

COVER ATTACHMENT FOR RECEPTACLES.

1,187,866.

Specification of Letters Patent. Patented June 20, 1916.

Application filed December 1, 1913. Serial No. 804,034.

To all whom it may concern:

Be it known that I, CHARLES F. SCHNEBELIN, citizen of the United States, residing at Peoria, in the county of Peoria and State of Illinois, have invented certain new and useful Improvements in Cover Attachments for Receptacles; and I do hereby declare that the following is a full, clear, and exact description of the invention, which will enable others skilled in the art to which it appertains to make and use the same.

This invention relates to improvements in receptacles for displaying goods. It pertains more particularly, however, to a cake or cracker can and still more particularly to a detachable lid or cover for the same.

The object of the invention is to provide a lid or cover for a receptacle that may be attached and detached, and when attached will be firmly and rigidly held as though attached to the can by soldering or riveting.

Receptacles of this character usually include a solid metal lid or cover hingedly attached thereto. But when so attached the goods cannot be displayed to the purchaser except from openings in the front of the can itself. It has been found to be an advantage to display the goods through the top of the can, or its lid, and therefore the lid or cover is now being provided with an opening covered with glass to protect the goods through which said goods may be displayed; but covers of this character are not suitable for shipping because of the danger of breaking the glass. A slip cover of metal is therefore provided for shipping purposes which is removed when it reaches the consumer and a display cover is substituted. This display cover must be so attached that it can be readily opened and closed and as strong as though soldered to the can. Consequently the means of attaching employed must be strong and such as will not permit the cover to sag or to have any looseness or movement upon the can other than the hinged movement.

My invention has for its object, therefore, to provide such a means of attachment and with this object in view I shall proceed to the description of the invention aided by the accompanying drawing, in which,

Figure 1 shows a can and its lid in perspective and my invention attached thereto. Fig. 2 shows a lid detached from the can and shown on a larger scale, my invention

being attached thereto. Fig. 3 is a vertical section of a portion of the can and its cover and the means of attaching the latter.

A represents the can or other receptacle and B its cover provided with a transparent plate B', one of whose edges or that adjacent the can is provided with a rolled integral tubular portion C to receive the two ends or terminals of an attaching member now to be described it being understood, however, that the tubular portion C may be replaced by some other equivalent means or structure which will firmly hold said member. This said member consists preferably of a single length of wire whose ends extend toward one another, substantially as indicated by dotted lines at D D in Fig. 2, where they are inclosed by the said tubular portion C of the lid or cover. Those parts of the wire having the said ends are bent substantially at right angles to the ends within the part C and both lie in the same plane and are indicated by E. They are again bent substantially at right angles in that plane into the parts F and thence again substantially at right angles into G parallel to the portions E and still in the same plane, the wire being once bent more substantially at right angles into the parts H but in a plane lying substantially perpendicular to the plane of the parts E F G.

The portions of the wire last mentioned lie against the outer surface of the wall of the can while the parts H lie upon the top of the wall of the can which usually terminates in an inwardly extending overhanging lip or flange A', the wire being then turned downwardly and inwardly into the angling extensions J and thence into the portions K which normally lie against the inner surface of the can-wall, the wire thence being recurved and forming an upwardly extending loop consisting of two side portions L and an upper substantially horizontally disposed portion M. The parts L M may also lie upon the inner surface of the can-wall, the part M, in addition, lying beneath the said overhanging lip or flange A' and preferably against its under side. The wire is bent in such a manner that it snugly fits the can especially the said overhanging lip or flange A' so that there will be no looseness or shake, the portions H J lying against the overhanging lips or flanges A², at opposite sides of the can, as

shown in Fig. 1 so that there can be no movement of the lid laterally in its own plane which would prevent its opposite sides B² readily passing down beside the 5 walls of the can in the closing movement.

The gage of the wire is sufficiently heavy to prevent rocking movement of the lid in its own plane, and the wire cannot lift from the can because the part M abuts upon 10 the underside of the lip or flange A'. It is thus seen that the lid will have firm attachment since there can be no movement in any direction.

In order to move the lid it is only necessary to grasp the part M between the thumb 15 and finger and draw it forward from beneath the lip or flange A' whereupon the parts J K can be sprung outward so as to permit the wire to be raised from the can 20 with the said lid or cover.

After the removal of the slip cover referred to, the attachment of the display lid is a matter of but a moment by reason of the simplicity of the structure employed and 25 the easy manner of attachment, transforming the can at once from a shipping can into a display can.

Having thus described my invention I 30 claim:—

30 1. In a lid or cover attaching means, the combination with a receptacle including a portion projecting from the top of one of the walls into the containing space of said receptacle, and a lid or cover, of a one piece 35 member of spring wire including an extension to which the cover is hinged, and including also a portion to lie against the outer surface of one of the walls and extending upward over the top edge of said wall, thence extending downward into the 40 receptacle and adapted to engage the inner surface of said wall, and terminating in an upwardly extending part whose terminus 45 is adapted to engage beneath the said projecting portion of the receptacle.

2. In a lid or cover attaching means, the combination with a receptacle including a portion projecting from the top of one of the walls into the containing space of said 50 receptacle, and a lid or cover, of a one piece member of spring wire including two spaced portions extending over the top of the wall and the said projecting portion and frictionally engaging the inner and outer sur-

faces of said wall, the outer depending portion having the lid hinged thereto at its lower terminus, the inner portion being recurved from its lower portion and terminating in an extension whose upper terminus is adapted to engage beneath the said projection for holding the member in place, the recurved portion adapted to be flexed from beneath the projection to release the said member and permit the removal of the 55 cover.

3. In a lid or cover attaching means, the combination with a receptacle including a portion extending from the inner surface of one of the walls of the same, and a lid having a depending flange to overlie the 60 outer surface of the upper portion of the described wall of the receptacle, of a member of spring wire hingedly connected with the depending flange of the lid or cover 65 including spaced extensions each formed into a loop, a part of each loop adapted to engage opposite sides of the wall portion of the receptacle and spaced from one another upon its inner wall, the member terminating in an elastic portion between the loops 70 adapted to engage beneath the inner extended portion of the said receptacle.

4. A lid or cover attaching device consisting of a single piece of spring wire, a portion thereof being straight for attachment to the lid or cover and at each end of the straight portion being bent into two spaced extensions lying substantially perpendicular to the said straight portion, the extension being thence bent into parallel 75 portions substantially perpendicular to the straight portion and perpendicular to the spaced extensions, thence being bent parallel to and spaced from said spaced extensions, thence being recurved and 80 terminating in a looped portion lying between the portions last formed and substantially in the same plane therewith, the terminus of the looped portion lying between 85 said extensions and close to a line extending 90 between said parallel portions.

In testimony whereof I affix my signature, in presence of two witnesses.

CHARLES F. SCHNEBELIN.
